UNITED STATES PATENT OFFICE.

EUGENE M. GANT, OF ETHEridge, TENNESSEE, ASSIGNOR TO THE E. M. GANT MFG. CO., OF ETHEridge, TENNESSEE, A CORPORATION OF TENNESSEE.

PUMP PLUNGER.

Application filed September 17, 1921. Serial No. 501,282.

To all whom it may concern:

Be it known that I, EUGENE M. GANT, a citizen of the United States, residing at Etheridge, in the county of Lawrence and 5 State of Tennessee, have invented certain new and useful Improvements in Pump Plungers, of which the following is a specification, reference being had to the accompanying drawings.

10 This invention relates to certain improvements in pump plungers, and it is an object of the invention to provide a device of this general character embodying a novel and improved structure whereby the same is in 15 swivelled connection with its coating rod, resulting in increased efficiency of the plunger and prolonging the life of the cup associated therewith.

Another object of the invention is to provide a novel and improved device of this 20 general character having a port therethrough which is closed by the stem during a compression stroke of the plunger and which is opened upon movement of the 25 plunger in the opposite direction.

The invention consists in the details of construction and in the combination and arrangement of the several parts of my improved pump plunger whereby certain important advantages are attained and the 30 device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying 40 drawings, wherein:

Figure 1 is a fragmentary view partly in section and partly in elevation illustrating a plunger constructed in accordance with an embodiment of my invention and applied 45 within a cylinder;

Figure 2 is a view similar to Figure 1 showing certain of the parts in a second position;

Figure 3 is a sectional view taken substantially on the line 3—3 of Figure 1; and

Figure 4 is a view in perspective of the nut herein disclosed.

My improved plunger as herein disclosed comprises an annular band or sleeve 1 in 55 which is adapted to be threaded a plug 2, the

outer end of said plug being provided with an outstanding annular flange 3 so that a leather washer or cup 4 may have its inner marginal portion effectively clamped between said flange 3 and the adjacent end of the member or sleeve 1 when the plunger is 60 assembled.

The inner face of the plug 2 is provided at its axial center with a socket or chamber 5 and disposed through the bottom of said 65 socket or chamber 5 at the axial center thereof is a nipple or vent tube 6 extending inwardly of the socket or chamber 5 and terminating a desired distance above the bottom of the chamber 5. The outer end portion of the nipple or vent tube 6 is substantially 70 flush with the outer face of the plug 2.

S denotes an operating stem provided at its inserted end portion with an annular enlargement or head 7, said end portion of the 75 stem S extending within the socket or chamber 5. Loosely surrounding the stem S inwardly of the head or enlargement 7 is a nut 8 adapted to be threaded within the socket or chamber 5 whereby the stem S and plug 80 2 are in swivelled connection. The inserted end of the stem S at its axial center is provided with a recess or socket 9 in which is adapted to extend the adjacent end portion of the nipple or tube 6 so that upon movement of the plug 2, together with the parts carried thereby, during a compression stroke, the stem S closes the flow through the nipple or tube 6.

To facilitate this closure, a gasket or 90 washer 10 surrounds the nipple or plug 6 at the bottom of the chamber or socket 5 for contact with the inserted end of the stem S. The socket or chamber 5 is of a depth to permit the plug 2 and the parts carried thereby 95 to have limited movement lengthwise of the stem S so that, upon retrograde movement of the stem S, the air within the pump cylinder will pass through the nipple or vent tube 6 to the compression side of the plunger. 100

To facilitate this passage of the air, the plunger immediately adjacent the enlargement or head 7 is reduced in thickness to provide the flattened faces a, said faces being of a length to extend beyond the applied nut 105 8. When the plug 2 is at the limit of its movement to permit the opening of the nipple or tube 6, the enlargement or head 7 has substantially close contact with the inserted end of the applied nut 8 and in order that 110

the desired passage of air may be obtained, the inserted marginal portion or edge of the applied nut 8 is provided with the notches or recesses 11 providing the requisite ports or bypasses for the air.

5 The assembled annular band or sleeve 1 and plug 2 provide a plunger head or piston and it is to be particularly noted that the plug 2, when applied, does not extend beyond the inner or compression side of the 10 annular band or sleeve 1 so that the plunger head or piston may have movement to the extreme compression end of the associated cylinder and which in itself is of particular 15 importance in practice.

From the foregoing description it is thought to be obvious that a pump plunger constructed in accordance with my invention is particularly well adapted for use by 20 reason of the convenience and facility with which it may be assembled and operated, and it will also be obvious that my invention is susceptible of some change and modification without departing from the principles and 25 spirit thereof and for this reason I do not wish to be understood as limiting myself to the precise arrangement and formation of the several parts herein shown in carrying out my invention in practice except as 30 hereinafter claimed.

I claim:

1. A pump plunger comprising, in combination, a member, a cup washer associated therewith, said member on its inner face being provided with a socket, a nipple disposed through the member and terminating within the socket, said nipple forming an air port through the member, a stem having an end portion extending within the socket, 40 and coacting means carried by the stem and member for holding the same in swivelled connection, said member having limited movement lengthwise of the stem, said stem, upon movement of the member in one direction, closing the flow through the nipple.

2. A pump plunger comprising, in combination, a member, a cup washer associated therewith, said member on its inner face being provided with a socket, a nipple disposed through the member and terminating within the socket, said nipple forming an air port through the member, a stem having an end portion extending within the socket, and coacting means carried by the 50 stem and member for holding the same in

swivelled connection, said member having limited movement lengthwise of the stem, said stem, upon movement of the member in one direction, closing the flow through the nipple, the end portion of the stem extending within the socket having a flattened face to provide a port for the passage of air. 60

3. A pump plunger comprising, in combination, a member, a cup washer associated therewith, said member on its inner face being provided with a socket, a nipple disposed through the member and terminating within the socket, said nipple forming an air port through the member, a stem having an end portion extending within the 70 socket, said inserted end portion being provided with an enlargement, a nut surrounding the stem and engaged within the socket whereby the stem and member are held in swivelled connection, the socket being of a 75 depth to permit the member to have limited movement lengthwise of the stem, said stem, upon movement of the member in one direction lengthwise of the stem, closing the flow through the nipple, said inserted end portion of the stem being reduced to provide a port leading from within the socket to one side of the member. 80

4. A pump plunger comprising, in combination, a member, a cup washer associated therewith, said member on its inner face being provided with a socket, a nipple disposed through the member and terminating within the socket, said nipple forming an air port through the member, a stem having an end portion extending within the socket, said inserted end portion being provided with an enlargement, a nut surrounding the stem and engaged within the socket whereby the stem and member are held in 90 swivelled connection, the socket being of a depth to permit the member to have limited movement lengthwise of the stem, said stem, upon movement of the member in one direction lengthwise of the stem, closing the 95 flow through the nipple, said inserted end portion of the stem being reduced to provide a port leading from within the socket to one side of the member, the inserted edge of the nut having a recess to provide 100 an air passage. 105

In testimony whereof I hereunto affix my signature.

EUGENE M. GANT.
